UNITED STATES PATENT OFFICE.

JOSEPH P. CLEAL, OF DAYTON, OHIO, ASSIGNOR TO THE NATIONAL CASH REGISTER COMPANY, OF SAME PLACE.

COIN-DISPLAYER.

SPECIFICATION forming part of Letters Patent No. 609,411, dated August 23, 1898.

Application filed September 30, 1897. Serial No. 653,558. (No model.)

To all whom it may concern:

Be it known that I, JOSEPH P. CLEAL, a citizen of the United States, residing at Dayton, in the county of Montgomery and State of Ohio, have invented certain new and useful Improvements in Coin-Displayers; and I do hereby declare the following to be a full, clear, and exact description of the invention.

My improvement relates to a coin-displayer 10 as applied to an autographic register or other similar device.

The specific object of my invention is to apply to such a machine a coin-displayer which shall be moved by the actuating mechanism 15 of the said machine and which shall be provided with a number of compartments, so as to display the proceeds of all sales during several succeeding sales.

The other features of my invention will be 20 referred to at greater length, and particularly pointed out in the claims.

Referring to the drawings, Figure 1 shows a perspective view of my invention as applied to an autographic register with the top of the 25 register-case omitted. Fig. 2 shows a perspective view of the register with the top of the case on. Fig. 3 shows a top plan view of the register with the top of the case removed, also with part of the coin-displayer omitted 30 to show the operation of the parts that actuate the coin-displayer. Fig. 4 is a vertical section on the line 4-4 of Fig. 3. Fig. 5 is a detached top plan view of the revoluble coin-displayer. Fig. 6 is a detached perspective 35 view of the lids which alternately expose and close the compartments of the coin-displayer when the machine is operated. Fig. 7 is a perspective view clearly showing the actuating mechanism, including the ratchet-wheel, 40 which is rigidly secured to the bottom of the display-cylinders, the latter being omitted; and Fig. 8 represents an enlarged detail perspective view of the drawer-latch and operating mechanism and the winding-roller and its 45 operating mechanism.

In the drawings like letters of reference indicate identical parts in all the figures.

Referring now to the drawings, the letter A indicates various fixed parts of the case which 50 contains the operating mechanism, and B rep-

resents the usual cash-drawer, moving on rollers b.

The autographic register shown has the usual table C, over which the paper passes from the supply-roll D to the receiving-roll 55 E in the usual manner, and the operation of the machine is controlled by the operating-lever F.

The machine to which my invention is shown as applied is described in the patent 60 to J. Pfeifer, No. 491,784, and as, moreover, a number of machines like that shown are in daily use a specific description of the general machine will be omitted and only so 65 much given as is necessary to an understanding of my invention.

Referring to Fig. 2 of the drawings, it will be seen that the top hinged lid of the case is provided with the usual plate G, bearing a combination-lock controlling the operation of 70 the operating-lever F and having a slot g, through which amounts may be written upon the paper strip in the usual manner. To the left of the plate G is a circular rim H, which is secured to the upper side of the hinged 75 lid of the case and which supports a plate of glass h, which covers a circular hole through the lid which is immediately below it. The glass plate has a slot or chute h', through which articles may be dropped into the coin-displayer below.

The coin-displayer proper consists of a cylinder I, having four radially-extending partitions i, which support within the cylinder I a concentric cylinder I', which is also divided into four compartments by diametrical partitions i'. Within the cylinders I and I', therefore, are formed eight coin-displayer 85 compartments, each of which has its upper end open, but its lower end closed. The bottoms of the compartments of the outer cylinder I are closed by the doors i², while the bottoms of the inner compartments are closed by the doors i³. The outer compartments have inclined sides i⁴, so that when a coin or 90 bill is dropped into the compartment it will slide down and rest upon one of the doors i². The doors of both the inner and outer compartments have radially-extending hinges i⁵.

The coin-displayers rest upon two concen- 100

tric circular tracks $J J'$. The supports, however, do not form a complete circle, but are broken, so as to leave no support over the hole J^2 in the partition J^3 , which separates the drawer-compartments from the rest of the machine. When the drawer is in normal position, if anything be dropped through the hole J^2 it will fall directly into the cash-drawer. (See Fig. 4.) The coin-displayer is centrally journaled upon a bolt or stud J^4 , which is secured to the bracket j (see Fig. 4) and which passes through the central post J^5 of the coin-displayer cylinder. At the lower end of the said post is the ratchet K , (see Figs. 4 and 5,) with which coöperates the retaining-pawl k , (see Fig. 7,) which is pivoted to the frame j and spring-actuated in the usual manner.

The winding-roller E is provided at one end with a ratchet-wheel l^2 , which is engaged by an operating-pawl l^3 , mounted on a pivoted lever l^4 , the lower end of which projects into the path of the money-drawer, so that when the latter is closed the pawl will be operated to move said winding-roller. A suitable spring is connected to the lever l^4 , so as to normally force the pawl into a retracted position. A spring-pressed crank-arm l^5 is pivoted on the frame and is provided with a projecting stud l^6 , which engages and locks the ratchet l^2 against backward movement. The lever is rigidly secured at its lower end upon the right-hand end of the shaft l , which passes centrally through the storage-roll E . The shaft is journaled in suitable bearings in the brackets l' , and upon its left-hand end is secured a forwardly-extending horizontal arm L' , which when the operating-lever F is actuated depresses the forward end of the pivoted lower operating-lever M , raising the rear end thereof with the drawer-plunger m , carried thereby, by which the cash-drawer is released in the usual manner. Secured also rigidly upon the left-hand end of the shaft l is a downwardly-extending arm l' , the lower end of which extends down in front of and rests against the right-hand end of the arm N of a bell-crank, which is pivoted at N' . The arm N^2 of this lever is connected with the track J' by a coil-spring k' , so that said arm is normally drawn forward and is also loosely pivoted to the sliding bar O , which carries the actuating-pawl o , which coöperates with the ratchet K . If the lever F be moved forward, the shaft l is rocked, which springs the downwardly-extending arm l' rearwardly, which in turn actuates the bell-crank to slide the bar O toward the right, as will be readily understood. As the pawl o engages the ratchet K , carried by the coin-displayer cylinder, the coin-displayer will be turned one step at each forward movement of the operating-lever.

An important feature of my invention relates to the means employed for controlling the step-by-step movement of the coin-displayer, so that the various compartments of

the special cylinder will be successively moved under the chute h regardless of the force with which the operating-lever may be actuated. To this end the fixed bracket j is provided with a slot j^2 , arranged at such a distance from the center of rotation of the cylinder I that the downwardly-projecting stops j^3 , of which there are eight, being one for each of the coin-displayer compartments, would pass through the slot when the cylinder is turned. The sliding bar O has also a slot o^2 , inclined as shown in Fig. 3. The slot o^2 is normally closer to the stud J^4 than the distance between the said stud and the stops j^3 , and when the operating-lever F is actuated the cylinder I will not be able to move until the sliding bar has been moved to the right by the movement of the lever F far enough to permit the adjacent stop on the cylinder to pass through the slot o^2 in the sliding bar. It of course then passes on through the slot J^2 , and the succeeding stops j^3 approach the sliding bar. As it does so, however, the sliding bar is moved farther to the right, and by the time the approaching stop reaches the sliding bar the slot o^2 will have been moved so far to the right that the stop cannot pass therethrough, but strikes against the side of the sliding bar and comes to rest, nor can it be moved until the operating-lever is returned to normal position and again actuated, as already described.

The pawl O when in its retracted position rests upon the incline portion of one of the long teeth of the ratchet-wheel K and is capable of a slight movement before it engages the operating portion of a ratchet-tooth. This lost motion in respect to the ratchet-wheel permits the bar O to be moved sufficiently to bring the notch o^2 into the proper position to allow one of the projections j^3 of the displayer to pass before the movement of the said displayer is commenced.

The coin-displayer compartments are so positioned with respect to the stops j^3 that when operating the machine if any stop strikes the side of the sliding bar, thereby bringing the cylinder to rest, one of the coin-displayer compartments will be brought to rest just before reaching the chute h .

Secured to the partition J^3 , near the cylinder I and a short distance to one side of the slot h' , is a vertical post P , to the top of which is secured at one end a radially-extending shaft p , which is secured at its other end in the upper end of the bolt or stud J^4 . Hung loosely upon the shaft p and normally depending into an inner and an outer coin-compartment are the two shields $P' P^2$, which, were they both to be placed in horizontal positions, would close the slot or chute h' ; but by means which I shall presently describe I have so arranged the parts that only one of the shields is in horizontal position at a time. When one is held in horizontal position, the other is dropped, and vice versa. The outer shield P' operates to alternately

open and close the portion of the slot or chute h' which communicates with the outer coin-compartments, and the inner shield P^2 operates in the same manner with respect to the 5 portion of the slot communicating with the inner coin-compartments. I accomplish the opening and closing of the shields P' and P^2 by my arrangement of the partitions i and i' of the cylinders I and I'. The partitions separating the compartments of the respective cylinders are not in line with each other, but each partition is located at a point midway between two of the partitions of the other cylinder, so that each outer compartment is 10 opposite portions of two inner compartments, and vice versa, as clearly shown in Figs. 1 and 2. Hence as the two concentric cylinders are rotated on the common axis the partitions of the respective cylinders will pass alternately 15 beneath and in line with slot or chute h' . Just before a partition reaches the said slot, however, it comes in contact with one of the depending plates or shields P' P^2 and pushes it up into a horizontal position against the 20 portion of the slot communicating with the corresponding cylinder-compartments. As the partition which actuates the shield passes from beneath the slot or chute h' the said shield drops therefrom and leaves that portion of the slot open, and simultaneously the other shield is elevated and closes the corresponding portion of the slot. Hence it will be seen that the slot or chute h' never communicates with compartments of both cylinders at the same time, but with one of each 25 alternately.

As hereinbefore stated, the bottoms of the several coin-compartments consist of hinged doors i^2 and i^3 . These are held closed by the 30 display-supporting tracks J J' , upon which they rest in their closed position. When the display is rotated and a compartment of either cylinder passes over the broken-away portion of the corresponding track over the 35 hole which communicates with the cash-drawer, (which broken-away portions of the tracks are to one side of the deposit-slot h' and substantially opposite the post P ,) the bottom of said compartment drops open and 40 anything thereon is cast into the cash-drawer. It is then closed at the next step of the coin-displayer, being pushed to by coming in contact with the end of the supporting-track, and the bottom of a compartment in the other 45 cylinder next opens in view of the relative arrangement of compartments before described, and it will appear from the foregoing and by reference to the drawings that when the bottom of a compartment is open the portion of the slot h' over the same will be closed, so that no money can be dropped directly 50 from the slot into the cash-drawer.

The operation of my device is as follows: When the proceeds of a sale are deposited 55 into the desired compartment through the slot h' , the lever F is operated to release the cash-drawer and advance the coin-displayer

one step by virtue of the mechanism described. The display being rotated in a direction which first moves the compartment 70 containing the coin away from the opening into the cash-drawer, the coin or bill deposited is kept in view in its compartment through the glass top of the cylinder during several succeeding sales or until said compartment is finally moved step by step to the broken-away portion of the supporting-track and the opening into the cash-drawer, when the contents are deposited into the drawer as 75 the hinged bottom of the compartment drops 80 open.

The outer compartments of the coin-displayer are preferably used for money of large denomination and the inner compartments 85 for smaller coins.

It will thus be seen that I have produced a simple and efficient device for displaying coins. I do not, however, limit myself to the exact construction herein set forth, as it may be somewhat modified without departing 90 from the spirit of my invention.

I claim as my invention—

1. A coin-displayer for autographic registers or the like consisting of a rotatable outer casing divided into several compartments 95 each being provided with a hinged bottom which automatically opens as the corresponding compartment is brought over a given point, substantially as and for the purpose set forth.

2. In a coin-displayer for autographic registers, the combination with a suitable containing-casing, of a movable casing arranged within the same and having an inner and an outer series of compartments, a cash-drawer 105 and means for bringing a compartment of each series alternately into connection with said cash-drawer.

3. In an autographic register or the like, a cash-drawer, and a lid provided with a slot 110 communicating with said drawer, in combination with a movable coin-displayer between the drawer and slot having an inner and an outer series of compartments one of each of said series of compartments being brought 115 successively into register with the said slot, substantially as set forth.

4. In an autographic register or the like, a cash-drawer, a lid provided with a slot communicating with the said drawer, a movable 120 coin-displayer between the drawer and slot having an inner and outer series of compartments one of each of said series of compartments being brought successively into register with the slot, in combination with means 125 actuated by the movement of the display for alternately opening and closing each portion of the slot registering with the inner and outer compartments respectively, substantially as set forth.

5. In an autographic register or the like, a coin-displayer having inner and outer adjacent compartments communicating with a slot in the register-case, in combination with

- means for moving the display step by step whereby an inner and an outer compartment are alternately brought into direct register with the said slot, substantially as set forth.
- 5 6. A coin-displayer for autographic registers and the like, having inner and outer compartments communicating with a slot in the register-case and with a cash-drawer, said compartments being provided with hinged bottoms which successively open into the said drawer, in combination with means for closing the said slot over a compartment when its bottom is open, substantially as set forth.
- 10 7. An autographic register and coin-displayer, or the like, comprising an outer case provided with a coin-chute, a series of revolving cash-trays, means for moving the same, to which said trays are fulcrumed, a supporting-rail which prevents the tilting of the trays during a portion of their revolution, an operating-lever and record-strip, and means by virtue of which the said cash-trays and record-strip are actuated, substantially as set forth.
- 15 8. An autographic register and coin-displayer, or the like, having a circular revolving series of cash-trays, means whereby the said trays are held in a substantially horizontal position in the same plane and to which said trays are fulcrumed at their inner ends, and means for guiding the outer ends of the trays in their movement, a record-strip, a
- 10 9. In an autographic register and coin-displayer, or the like, the combination of a case having a coin-chute and an opening for movable record-tape at its top, a crown-wheel provided with ratchet-teeth and carried by a drum which holds the record-tape, an operating-lever extending through the top of the register-case and cooperating with the said ratchet crown-wheel, a series of cash-trays supported beneath the said coin-chute, and means actuated by the said operating-lever for moving the said trays successively past the said coin-chute, substantially as set forth.
- 15 10. In an autographic register and coin-displayer, or the like, a revolving series of cash-trays, a spindle, a hub rotating on said spindle to which the trays are fulcrumed and having a ratchet crown-wheel, and means cooperating with the ratchet crown-wheel for actuating the same to revolve the cash-trays, substantially as set forth.
- 20 3. In testimony whereof I affix my signature in presence of two witnesses.
- JOSEPH P. CLEAL.
